HOWARD W. WELLES, OF POUGHKEEPSIE, NEW YORK.

DESIGN FOR A CAMPAIGN-BADGE.

SPECIFICATION forming part of Design No. 21,814, dated August 30, 1892.

Application filed July 19, 1892. Serial No. 440,541. Term of patent 3½ years.

To all whom it may concern:

Be it known that I, HOWARD W. WELLES, a citizen of the United States, residing at Poughkeepsie, in the county of Dutchess and State of New York, have invented and produced a new and original Design for Campaign-Badges; and I do hereby declare the following to be a full, clear, and exact description of the same, reference being had to the accompanying drawing, forming a part thereof.

The figure is a front elevation of a campaign-badge, showing my design.

The leading feature of my design is a bust representation of Grover Cleveland surrounded by the two emblems of good luck, the horseshoe and the four-leaf clover.

A, B, C, and D represent the four clover-leaves, terminating in the stem S; E, the horseshoe, having the usual calk M and nail-holes N, and F represents the inclosed bust of Grover Cleveland. The four clover-leaves are arranged as shown and have two leaves opposite the face.

What I claim is—

The design for a campaign-badge, as herein shown and described.

In testimony whereof I affix my signature in presence of two witnesses.

HOWARD W. WELLES.
